United States Patent Office

Des. 206,868
Patented Feb. 7, 1967

206,868

CIRCULAR SHELTER

Eliot F. Noyes, New Canaan, Conn., assignor to Mobil
Oil Corporation, a corporation of New York

Filed Mar. 21, 1966, Ser. No. 1,582

Term of patent 14 years

(Cl. D13—1)

FIG. 1

FIG. 2

FIGURE 1 is a top perspective view of a circular shelter showing my new design;

FIGURE 2 is a bottom perspective view of the circular shelter with its supporting column shown fragmentarily for convenience of illustration.

I claim:

The ornamental design for a circular shelter, as shown and described.
